UNITED STATES PATENT OFFICE

JOHN W. SAWYER AND BERT E. LARGE, OF ASHLAND, NEBRASKA

DESIGN FOR A MULE HAZARD

Application filed October 27, 1930. Serial No. 37,406. Term of patent 3½ years.

To all whom it may concern:

Be it known that we, JOHN W. SAWYER and BERT E. LARGE, citizens of the United States, residing at Ashland, in the county of Saunders and State of Nebraska, have invented a new, original, and ornamental Design for Mule Hazards, of which the following is a specification, reference being had to the accompanying drawing, forming part thereof.

Figure 1 is a view in side elevation of the mule hazard.

Figure 2 is an edge view of the mule hazard.

We claim:

The ornamental design for a mule hazard, as shown.

BERT E. LARGE.
JOHN W. SAWYER.
